CLAIM

The ornamental design for a docking bay electrical outlet unit, as shown and described.

DESCRIPTION

U.S. patent application Ser. No. 13/043,455 filed on Mar. 8, 2011 and U.S. patent application Ser. No. 12/726,724 filed on Apr. 27, 2010.

FIG. 1 is a front perspective view showing my new design;

FIG. 2 is a front side view thereof;

FIG. 3 is a back side view thereof;

FIG. 4 is a right side view thereof;

FIG. 5 is a left side view thereof;

FIG. 6 is a top side view thereof; and,

FIG. 7 is a bottom side view thereof.

The broken lines in the Figures are for illustrative purposes only and form no part of the claimed design.
